UNITED STATES PATENT OFFICE

GEORGE HENRY WHEARY, OF RACINE, WISCONSIN, ASSIGNOR TO WHEARY TRUNK COMPANY, OF RACINE, WISCONSIN, A CORPORATION OF WISCONSIN

HAND LUGGAGE

Application filed June 11, 1930. Serial No. 460,412.

This invention relates to certain new and useful improvements in hand luggage and has as an object the provision of an improved case whereby one or more man's suits may be readily carried without wrinkling and at the same time provide ample space for other articles without increasing the overall size or weight of the case.

10 Another object of the invention is to produce a suitcase or similar device in which the suit may be placed and tension applied thereto in order to eliminate wrinkles from the suit prior to closing.

15 Another object of this invention resides in the provision of improved means for attaching the removable garment holder or hanger in the case to avoid shifting of the suit or suits during closing of the case.

20 With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

30 In the accompanying drawings, I have illustrated one complete example of the physical embodiment of my invention constructed according to the best mode I have so far devised for the practical application of the principles thereof, and in which:

Figure 1 is a perspective view of a man's case embodying my invention, the case being shown in open position with one man's suit in the position it occupies just prior to being folded over the supporting frame or form, and the cover being broken away;

Figure 2 is an end view of my improved case, with parts broken away and in section and illustrating the cover in open position with two man's suits in place;

Figure 3 is an end view similar to Figure 2 but showing the cover closed; and

Figure 4 is a fragmentary, detail view of a hanger showing the improved means for attaching the same in the case.

Referring now more particularly to the accompanying drawings, in which like numerals designate like parts throughout the several views, the numeral 5 represents the main section of a luggage carrier of the hand case type having a cover 6 hingedly connected therewith along one marginal edge, as at 7.

As is customary, the case is provided with a conventional handle 8 and locking devices 9. The interior of the main section may be suitably partitioned according to the requirements for which it is constructed, and in the present instance a partition 10 is removably mounted in the main section parallel with and spaced from its front wall 11 by guides 12, there being a suitable cover 13 hingedly mounted to close the compartment or space 14 provided between the partition 10 and the front wall 11. If desired the compartment 14 may be sub-divided in any suitable manner.

Provision is made for carrying one or more complete man's suits (two in the present instance) over the top of the main section and in the cover 6 when closed, the garments being so positioned and held within the case by means of a garment carrying or supporting frame 15 and cooperating suit hangers 16, that when removed from the case they are as neat and unwrinkled as when placed therein. The frame 15 is substantially U shaped and the side arms 17 thereof have their inner ends 18 directed upwardly at an angle when the frame is in a horizontal position over the main section, and pivoted, as at 19, to the upper rearwardly inclined ends 20 of attaching members 21 which are removably secured in channel members or guides 22 secured to the side walls of the main section adjacent their rear inner ends.

The closed end of the U shaped garment carrying or supporting frame has a substantially circular bar 23 secured thereto which is preferably padded or covered with a soft yieldable material 24 to prevent creasing of a garment 25 having its medial portion folded thereover in a manner later described, and the ends of the bar 23 are preferably provided with guards 26 to prevent sidewise movement of the suits off of the ends thereof.

The frame 15 is of such size that when it

is swung to a horizontal position over the main section 5, the bar 23 will be adjacent to the front wall 11 but spaced therefrom a distance sufficient to allow for the thickness of 5 the suits folded thereover, and when the cover 6 is open, in which position it is held by a suitable collapsible support 27, and the frame swung vertically, the bar 23 will pass a line drawn vertically through the pivot 19 and 10 thus rest against the cover.

The hangers 16 are each substantially conventional man's coat hangers having a top portion 28 of a shape to fit the shoulders of a coat and vest and a transverse bar 29 over 15 which trousers may be draped. A T shaped head or fastener 30 is secured to each hanger by means of a flexible strap 31, the head or fastener being engageable in a T slot formed in a keeper 32 which is centrally mounted in 20 the rear portion of the cover adjacent its hinged connection with the main section.

The T shaped slot in the keeper 32 is elongated to extend throughout the length of its portion 33 which parallels the top wall 34 of 25 the cover and the head of the T slot is in the transverse portion of the keeper which parallels the rear end wall 35 of the cover, so that when the cover is open and a hanger is attached by having its T head 30 engaged with 30 the keeper 32, tension may be applied thereto to facilitate straightening and arranging the suit during packing. The hanger, for convenience, is also provided with a pivoted hook 35 to permit its use apart from the case, as 35 will be readily apparent.

In arranging a suit in the case, the trousers are neatly draped over the bar 29 of the hanger, the coat and vest next placed thereon in the conventional manner, and the T 40 shaped head or fastener 30 secured in the keeper 32, the frame having been first placed in its horizontal position over the main section. The suit is then straightened out in the manner illustrated in Figure 1 so as to avoid 45 creases and folds except in the customary places and the frame is then swung upwardly on its pivot causing the suit to fold about the bar 23 in the manner illustrated in Figure 2.

50 A board 36 or other suitable retaining means is then detachably connected with the side arms 17 of the frame 15 by fastenings 37, to hold the lower ends of the coat and trousers against their upper end portions, 55 the board 36 also preventing the ends of the coat from dropping into the main section of the case when the frame 15 is moved thereover.

When more than one suit is to be carried 60 in the case, the second suit is arranged on its hanger and secured in place over the first suit when the same is in its position illustrated in Figure 1, and it is noted that the flexible strap 31 of the hanger on which the 65 second suit is hung is preferably longer than

that of the other hanger, so that the shoulder portions of the suits are not superposed. This materially reduces the combined thickness of the suits. The second suit is then 70 also neatly folded in the manner shown in Figure 1 and the frame then swung vertically as previously described and the bottom ends of the garments secured in place by the board 36.

75 After the suits have been properly arranged, it is of course undesirable to shift, or in any way derange them; but in luggage heretofore proposed for the carrying of man's suits, the manner of attaching the garment supporting structure within the case resulted in shifting of the same as the cover was closed, so that very often the garments were wrinkled and mussed.

80 The present invention entirely eliminates this undesirable feature in that the flexible straps which connect the hangers 16 with the keeper 32 accommodate the movement of the keeper toward the hangers and permit the cover 6 to be closed, after the supporting frame is moved to its horizontal position as 85 illustrated in Figure 2, without imparting movement to the hangers and consequently the garments arranged thereon, the straps folding and doubling up as shown in Figure 3. Closing of the case therefore does not in 90 any way disturb the neat and desired arrangement of the suits, and as the case is carried and ordinarily rests in a position with the bar 23 of the supporting frame 15 uppermost, it is obvious that there is never any 95 tendency toward shifting of the suits from their proper positions draped over the bar 23.

100 From the foregoing description, it will be readily apparent to those skilled in the art 105 to which an invention of the character described appertains, that I provide an improved type of hand luggage especially adapted for men's use and having means whereby one or more complete suits may be 110 carried without wrinkling and without unduly increasing the size or overall weight of the case.

115 It is also readily apparent that by providing flexible means of attachment for the garment hangers, shifting of the garments after they have been properly arranged is entirely eliminated.

What I claim as my invention is:

120 1. In a hand luggage case including a main section and a cover therefor, means for supporting garments within the case comprising, a rigid self-supporting garment carrier having a part over which garments may be folded, means mounting said carrier in the 125 case so that the carrier is held stationary in the case when closed, a garment receiving member upon which garments are draped preparatory to being folded over said carrier part, means for connecting the gar- 130

ment receiving member with the cover of the case to facilitate arrangement of the garments on said carrier, the point of connection of said means with the cover moving toward a garment on the carrier during closing of the cover, and said connecting means being flexible whereby the garment receiving member remains stationary within the garment during closing of the cover.

10 2. In a hand luggage case of the character described including a main section and a cover hingedly connected therewith, supporting means for garments to be carried in said case comprising a supporting frame, 15 garment hangers on which the garments are mounted preparatory to being placed on said supporting frame, and flexible means for securing the garment hangers in the case, said flexible means of different garment hangers 20 being of different lengths whereby the garment hangers are disposed in staggered relation.

3. In a hand luggage case of the character described, including a main section and a cover hingedly connected therewith, garment retaining means within the case comprising a frame substantially stationary in the case when closed and having a part over which a garment may be folded, a garment 25 hanger upon which the garment is draped preparatory to being folded over the frame part, keeper means carried by the cover, said keeper means being so positioned on the cover as to move toward the frame during 30 closing of the cover, and flexible means for connecting the garment hanger with the keeper means, whereby tension may be applied to the garment between the frame part and the garment hanger during arrangement 35 of the garment on the frame and whereby the garment hanger is free to remain stationary during shifting of the keeper means, incidental to closing of the cover, so that the garment is not deranged by closing of the 40 cover.

50

55

60

65

4. In a hand luggage case of the character described, including hingedly connected sections, a garment supporting unit having a part over which garments are adapted to be folded, means mounting said unit in one section so that the unit has a definite substantially fixed position in said section when the case is closed, a garment hanger upon which garments are draped preparatory to being folded over said unit part, an attaching member mounted on the interior of the other hinged section adjacent the hinged connection but in a position at which said attaching member moves toward the unit part during closing of the case, and a collapsible connection between the garment hanger and the attaching member, said collapsible connection enabling application of tension to the garment draped over the hanger to facilitate its arrangement on the garment supporting unit and accommodating the shifting of the attaching member toward said unit part during the closing of the case while enabling the garment hanger to remain stationary with the garment and said supporting unit.

5. In a hand luggage case including hingedly connected sections, the combination of a garment supporting frame mounted in one section and adapted to have garments draped thereon, a garment hanger adapted to have garments draped thereon preparatory to their arrangement on the frame, and a flexible connection mounting said garment hanger in the other section, said flexible connection holding the garment hanger so as to accommodate arrangement of the garment on the frame during packing and enabling the garment hanger to remain stationary with respect to the garment during closing of the case.
